CARBURETING MECHANISM

William L. Howe, Jr., Chesterfield, Mo.

Application May 24, 1950, Serial No. 163,946

4 Claims. (Cl. 261—69)

1

This invention relates to carbureting mechanisms, and has for its principal object to provide an extremely simple mechanism, highly efficient in operation and economical in the use of motor fuel.

Another object of the invention is to provide a very simple means for supplying the proper amount of air to vaporized motor fuel when the same is introduced into the mixing chamber of my new carbureting mechanism. Still another object is to provide a carbureting mechanism that is easily removable by taking out a few screws and two threaded members, whereby the entire assembly may be bodily removed from the surrounding and supporting casing for examination or repair. Still another object is to dispense with the float chamber present in most carburetors.

In the drawing:

Fig. 1 is a cross-sectional, vertical view taken through my carbureting mechanism in closed position.

Fig. 2 is a detailed, cross-sectional view taken on line 2—2, Fig. 1.

Fig. 3 is a detailed, cross-sectional view taken on line 3—3, Fig. 2.

Fig. 4 is a top plan view, partly in section, taken on line 4—4, Fig. 1.

Fig. 5 is an enlarged detail section taken through the fuel control valve mechanism in open position.

Fig. 6 is an enlarged, detailed, sectional view taken through the valve plunger and the tubular chamber in which it moves, taken on line 6—6, Fig. 5.

So far as I am aware, standard carburetors on the market depend on the heated air from the motor manifold to supply heat to properly gasify liquid fuel. In my carbureting mechanism the vaporized liquid fuel is sprayed out under pressure in such a fine mist, or fog, that when commingled with the air in the mixing chamber of my carburetor it passes through the manifold of the motor and into the several cylinders of the motor, and while the temperature of the mixture is raised due to the heat in the manifold, it is in such condition of vaporization that the mixture is immediately ignitable by the cylinder spark plug. I thus provide for a better combustion of the mixture with more efficient operation of the motor and with a saving in the liquid fuel. Said liquid fuel is admitted to the mixing chamber of my carbureting mechanism in a predetermined quantity under 100 pounds pressure when the metering valve is in its fully opened position,

2

vaporized and mixed with metered air prior to entering the manifold and into the cylinders of the motor.

My invention comprises a casing A, preferably a casting, consisting of two chambers B and C, respectively, and a base portion D having a flange E at the lower end thereof, whereby my device can be mounted on an internal combustion motor by means of bolts passing through holes F 10 in said flange E.

A fuel line 1 extends from a fuel supply tank (not shown) to the bottom portion 2 of member 3, which is provided with an outer circular shoulder 4, which is adapted to seat upon a circular flange 5 at the bottom of chamber C. A pressure pump, preferably electrically operated of a rotary type, capable of delivering a liquid fuel supply at a constant pressure of approximately 100 pounds per square inch through the atomizing discharge nozzles when the metering valve is in its fully opened position. The supply line has an upturned portion 6, which is threaded 20 secured in the bottom portion 2 of member 3. When member 3 is mounted on the flange 5, a lock nut 7 is threaded securely holding said member 3 in position in the chamber C. The member 3 has a central, vertical opening 8, therein extending from the top to the bottom thereof. The upper end of said opening 8 is enlarged to provide a substantially cup-shaped portion 9, and the lower end is threaded to receive a tubular plug 10, while the bottom portion of said opening 8 is enlarged as shown at 11 (Fig. 5) to receive 30 the outer end of the upturned portion 6 of fuel supply line 1. The upper end of opening 8 is reduced in diameter, as shown at 12, and an inclined portion 13 connects the portions 8 and 12 (Figs. 1 and 5).

40 Within the opening 8 is a metering pin 14, the lower end of which rests upon a coiled spring 15 which is supported on the upper end of plug 10, the purpose of said spring 15 being to return the metering pin 14 to its upper, closed position.

45 At the upper portion of metering pin 14 is a conically shaped tapered extension as shown at 16, which merges into a cylindrical smaller diameter upper end portion 17. The metering pin 14 is preferably hexagonally shaped longitudinally, as shown at 18, throughout the length of its greatest diameter to permit liquid fuel to pass through the opening 8, around the outer hexagonal surface of metering pin 14 when said metering pin 14 is depressed.

55 The upper end of metering pin 14 contacts a

small metal disk 19 secured to the central lower face of a diaphragm 20, and another small metal disk 19' is secured to the central upper face of said diaphragm 20 immediately above disk 19. The diaphragm 20 is preferably formed of tough plastic material which is elastic but not affected by contact with any liquid fuel that may be used in an internal combustion motor. The diaphragm 20 is placed on top of the member 3 (Figs. 1 and 5), and securely held in place by an upper cylindrical member 21, which has an outwardly extending flange 21' at the lower end thereof, and which member 21 rests upon the upper surface of diaphragm 20, and screws 22, passing through flange 21, and into the upper portion of member 3, securely hold said diaphragm in place. It will be noted that the upper surface of member 3 has an upwardly extending flange 23, to provide a circular recess to receive and retain diaphragm 20 in a fixed position between member 3 and cylindrical member 21 by means of the screws 22.

Cylindrical member 21 has a vertical tubular opening extending therethrough, preferably of larger diameter throughout most of its length to receive a floating plunger rod 24. At the lower end of plunger rod 24 is a smaller plunger rod 27, the lower end of which contacts the upper surface of disk 19', whereby the diaphragm 20 may be depressed at its middle portion when plunger 24 is moved downwardly.

The member 21 has an enlarged, cup-shaped portion 28 in the lower end thereof communicating with the vertical bore therein. The cup-shaped portion 28 and the cup-shaped portion 9 are in vertical alignment so as to provide a recessed portion to permit flexing of the diaphragm 20 when liquid fuel is permitted to enter the cup-shaped portion 9 when the metering pin 14 is depressed.

On the upper end of member 21 is pivotally mounted an arm 29, secured by a pivot 30 passing through two upwardly projecting ears 31 on said member 21. Also pivoted to said arm 29 is a roller 32, which is mounted in the bifurcated inner end of said arm. The roller 32 is preferably case hardened and is adapted to rest upon the upper end of plunger rod 24, which is also preferably case hardened.

The outer end of arm 29 is provided with a circular member 33, integral with said arm and having a screw-threaded vertical opening therethrough to receive a threaded bolt 34, which is provided with a lock nut 35, a head 36, and a washer 36. Between the head 35 and the washer 36 a circular, concave metal vane 37 is secured.

To the top of the casing A is secured a cover 38 by screws 39 positioned in the upper end of said casing. Situated above chamber B said cover 38 has an upwardly extending circular portion 40, which is interiorly screw-threaded to receive a tubular, outwardly screw-threaded member 41. A cross bar 42 is rigidly secured to the interior of the member 41 and has a cylindrical member 43, preferably as an integral part of said member, which is interiorly screw-threaded to receive a threaded bolt 44 having an enlarged lower end 45 and a grooved upper end 46, so that said bolt 44 may be rotated to the proper vertical position. The enlarged end 45 contacts the head 35 of the threaded bolt 34.

The purpose, or function, of the tubular member 41 is to regulate or meter the proper amount of air to be drawn into the mixing chamber B (Fig. 1). This is obtained by screwing said mem-

ber 41 downward or upward in the interiorly threaded circular portion 40. After adjustment has been made, bolt 44 is screwed upward or downward in cross bar member 43 and locked in place by lock nut N, in such position as to limit any further upward movement of the circular member 33 and arm member 29 beyond normal operating position, in the event of any blow back or backfire of the motor caused by faulty timing or other imperfections in the motor. There could never be any distortion of the plate member 37 due to a pressure created by any ordinary backfire because there is always an air passage between said plate member 37 and the tubular member 41, more than ample to relieve such pressure. This passage also is necessary to admit enough air therethrough to obtain perfect idling performance of the engine.

Projecting transversely and slightly upwardly from the member 3 is another fixed arm 47, which is provided with a longitudinal passageway 48 substantially its entire length. The inner end of the passageway 48 turns upwardly and connects with the cup-shaped opening 9 in the upper end of the member 3. The outer end of passageway 48 connects with a cross bar 49 (Fig. 2), having a tubular passageway 49' therein to the two enlarged ends 50 each having an enlarged central cavity 51 therein to accommodate a small amount of motor fuel and having a screw-threaded lower end 52, into which is screwed spray nozzle 53, which has a longitudinal small diameter bore 54 therein to connect with cavity 51. The passageway 49' also connects with cavity 51, whereby liquid fuel is supplied under substantial pressure of approximately 100 pounds per square inch to spray nozzles 53 when the valve 16 is fully opened by the amount of suction generated by the pistons in the cylinders of the motor, thereby forcing member 33 and arm 39 downward, by the downwardly moving air through member 41 against plate member 37.

In the reduced portion D of casing A there are two vertical openings 55, in each of which is placed a butterfly valve or shutter 56, carried by a tubular bar 57 rotatably mounted in bearings 58 in the lower end of reduced portion D. To one end of bar 57 a lever 59 is secured, which is operable either by the foot or hand of the operator of a motor vehicle in which my carbureting mechanism is mounted on the motor.

Also mounted in the portion D is a fuel supply member 60, which connects with the liquid fuel return line and which provides the proper amount of liquid fuel to be admixed with the proper amount of air in air passageway 61, which air is obtained from chamber B in casing A. The amount of mixed liquid fuel and air to be delivered to the motor is regulated by needle valve 62, which has a grooved head 63 whereby it may be rotated to admit more or less liquid fuel to the motor. For the idling operation of my carbureting mechanism fuel is vacuumed through the passage at the end of adjusting screw 62 connecting with the passage 61 and opening into portion D, through a bypass valve (not shown) connected to the return line which runs from the pressure pump relief valve to the liquid fuel supply tank, said bypass valve being connected to member 60. The purpose of the parts just described is to permit the motor to run slowly and keep running when the butterfly valves or shutters 56 are in a closed position, as shown particularly in Figs. 1, 2, and 3.

In the operation of my new carbureting mecha-

nism, when the operator of the motor vehicle desires to increase the speed of the motor he first operates the lever 59, which moves the butterfly valves or shutters 56 from substantially horizontal to a tilted position, which permits the suction generated by the pistons operating in the cylinders of the motor to draw air downwardly through cylinder 41 between the lower edge thereof and the outer downwardly inclined circular edge of cylindrical valve 37, which allows air to enter chamber B of casing A. This downward movement of the air forces vane 37 downwardly, thus depressing the outer end of arm 29, and causes roller 32 to press against the top of floating plunger rod 24 and the lower end 27, which depresses the center of diaphragm 20 and which also presses metering pin 14 downwardly, thereby unseating the valve 16, thereby permitting the liquid fuel under substantial pressure to flow through passageway 8, and enter the cupped opening 9, and thence through the passageway 48 to vaporizer spray nozzles 53, where due to the restricted bores 54 said liquid fuel is vaporized to a fine mist or fog-like consistency as it enters chamber B, where it is admixed thoroughly with the air in said chamber B to produce the predetermined correct mixture for admission into the cylinders of the motor. Before entering the motor cylinders, the mixture passes through the manifold (not shown) of the motor.

In order to vaporize the liquid fuel through the spray nozzles 53 and bores 54 into the air chamber B, I maintain through the electrically operated pump in fuel line 1 a pressure of approximately 100 pounds on the liquid fuel that passes through the fuel supply line 1, and into my carbureting mechanism (Fig. 2). Two spray nozzles 53 are attached to cross bar 49, to which one or more spray nozzles may be attached as desired.

When the valves or shutters 56 are substantially closed, that is, in a nearly horizontal position, the suction caused by the operation of the cylinders in the motor is cut off from air chamber B, which causes the outer end of arm 29 to rise and thus the release of pressure by roller 32 on the upper end of plunger rod 24, and the upward movement of metering pin 14 by spring 15, which returns the valve 16 of the metering pin 14 to its tapered seat, thus shutting off all flow of the liquid fuel to the vaporizing nozzles 53. Air is still permitted to enter chamber B by reason of the space between the edge of circular vane 37 and the lower end of cylinder 41.

By my new carbureting mechanism I provide better combustion and a definitely regulated supply of liquid fuel to the motor, thereby saving fuel, particularly at higher speeds and more rapid acceleration. The motor is more efficiently operated as it always receives the proper amount of admixed liquid fuel and air in the requisite mist-like condition for admittance into the cylinders of the motor. The size and number of the vaporizing spray nozzles 53 determines the maximum amount of the vaporized liquid fuel to enter air chamber B.

When removal of any of the parts is desired from my carbureting mechanism chambers B and C, all that is necessary to do is to unscrew the four screws 39 in the cover 38 and remove the cover 38, and also by removal of the locking nut 7 and unscrewing liquid fuel supply line 1 the associated parts in said chambers B and C may be removed.

I claim:

1. A carbureting mechanism comprising a casing provided with an air chamber, a tubular member mounted in a wall of said casing communicating with said air chamber, a support, an arm pivotally mounted on said support, a vane mounted on the free end of said arm and adjacent to but spaced apart from the inner end of said tubular member, a stop mounted in said tubular member to limit upward movement of said vane, a rod operable by said arm, a liquid tight diaphragm contactible on its upper face by the free end of said rod, a housing for slidably containing said rod, a second housing secured to said first named housing with said diaphragm securely contained between said housings, a metering pin slidably mounted in said second named housing beneath said diaphragm and adapted to be moved downwardly by said rod, a valve on said metering pin, a seat for said valve, said second named housing containing a passageway for liquid, a source of supply for said liquid, means for maintaining a substantial pressure on said liquid, an arm extending from said second named housing and provided with a longitudinal passageway therethrough, said passageway communicating at one end with said liquid passageway in said second named housing and at its other end with a transverse passageway in a nozzle supporting member, nozzles carried by said nozzle supporting member provided with restricted outlet passageways for discharging liquid in fog-like spray into said air chamber and means for moving said metering pin to open said valve thereon to permit the flow of liquid from said source of supply to said air chamber.

2. A carbureting mechanism comprising a casing provided with an air chamber, a tubular member mounted in a wall of said casing communicating with said air chamber, a support, an arm pivotally mounted on said support, a vane mounted on the free end of said arm and adjacent to but spaced apart from the inner end of said tubular member, a stop adjustably mounted in said tubular member to limit upward movement of said vane, a rod operable by said arm, a liquid tight diaphragm contactible on its upper face by the free end of said rod, a housing for slidably containing said rod, a second housing secured to said first named housing with said diaphragm securely contained between said housings, a metering pin slidably mounted in said second named housing beneath said diaphragm and adapted to be moved downwardly by said rod, a valve on said metering pin, a seat for said valve, said second named housing containing a passageway for liquid, a source of supply for said liquid, means for maintaining a substantial pressure on said liquid, an arm extending from said second named housing and provided with a longitudinal passageway therethrough, said passageway communicating at one end with said liquid passageway in said second named housing and at its other end with a transverse passageway in a nozzle supporting member, nozzles carried by said nozzle supporting member provided with restricted outlet passageways for discharging liquid in fog-like spray into said air chamber and means for moving said metering pin to open said valve thereon to permit the flow of liquid from said source of supply to said air chamber.

3. A carbureting mechanism comprising a casing provided with an air chamber, a tubular member adjustably mounted in a wall of said

casing communicating with said air chamber, a support, an arm pivotally mounted on said support, a vane mounted on the free end of said arm and adjacent to but spaced apart from the inner end of said tubular member, a stop mounted in said tubular member to limit upward movement of said vane, a rod operable by said arm, a liquid tight diaphragm contactible on its upper face by the free end of said rod, a housing for slidably containing said rod, a second housing secured to said first named housing with said diaphragm securely contained between said housings, a metering pin slidably mounted in said second named housing beneath said diaphragm and adapted to be moved downwardly by said rod, a valve on said metering pin, a seat for said valve, said second named housing containing a passageway for liquid, a source of supply for said liquid, means for maintaining a substantial pressure on said liquid, an arm extending from said second named housing and provided with a longitudinal passageway therethrough, said passageway communicating at one end with said liquid passageway in said second named housing and at its other end with a transverse passageway in a nozzle supporting member, nozzles carried by said nozzle supporting member provided with restricted outlet passageways for discharging liquid in fog-like spray into said air chamber and means for moving said metering pin to open said valve thereon to permit the flow of liquid from said source of supply to said air chamber.

4. A carbureting mechanism comprising a casing provided with an air chamber, a tubular member mounted in a wall of said casing communicating with said air chamber, a support, an arm pivotally mounted on said support, a vane mounted on the free end of said arm and adjacent to but spaced apart from the inner end of said tubular member, a stop mounted in said tubular member to limit upward movement of

said vane, a rod operable by said arm, a liquid tight diaphragm contactible on its upper face by the free end of said rod, a housing for slidably containing said rod, a second housing secured to said first named housing with said diaphragm securely contained between said housings, a metering pin slidably mounted in said second named housing beneath said diaphragm and adapted to be moved downwardly by said rod, a valve on said metering pin, a seat for said valve, said second housing containing a passageway for liquid, a source of supply for said liquid, means for maintaining a substantial pressure on said liquid, an arm extending from said second named housing and provided with a longitudinal passageway therethrough, said passageway communicating at one end with said liquid passageway in said second named housing and at its other end with a transverse passageway in a nozzle supporting member, nozzles carried by said nozzle supporting member provided with restricted outlet passageways for discharging liquid in fog-like spray into said air chamber, means for moving said metering pin to open said valve thereon to permit the flow of liquid from said source of supply to said air chamber and a spring for exerting pressure on said metering pin to return said valve to its closed position.
